UNITED STATES PATENT OFFICE.

ALADAR DE BAJZA, OF LONDON, ENGLAND.

AIRSHIP.

1,009,010.

Specification of Letters Patent. Patented Nov. 14, 1911.

Application filed August 2, 1910. Serial No. 575,064.

To all whom it may concern:

Be it known that I, ALADAR DE BAJZA, a subject of the King of Hungary, residing at 20 Hans road, London, England, gentleman, have invented certain new and useful Improvements in Airships, of which the following is a specification.

The primary object of this invention is to produce an air ship for military purposes which can be maneuvered to meet every possible contingency which may occur in actual warfare.

The invention is particularly applicable to air ships of the kind which are usually slightly heavier than air but which may, under some conditions, become lighter. Such ships according to the present invention are propelled and elevated or maintained at any definite altitude and kept in any definite course by means of fore and aft propellers which are mounted so that they can be turned positively in azimuth through any necessary angle in relation to the airship and also tilted vertically.

Usually two propellers would be used, one at each end of a car frame which extends from end to end of the gas envelop and is supported therefrom in a semi-rigid manner. Each engine and its associated propeller are mounted on a platform which can be turned in azimuth, and further, each propeller either with or independently of its associated engine is arranged so that it can be tilted in a vertical plane. By suitably setting the platforms and tilting the propellers, any desired movement of elevation either vertically or slantwise, or of depression, or of translation of the air ship may be effected.

The invention thus involves, besides the particular mounting of two independent sets of engines and propellers, a semi-rigid construction of air ship having a platform or frame extending the full length of the gas envelop, so that the engines may be mounted at the ends of the platform preferably at a place where the propellers may be elevated to such a height that the front propeller will create a partial vacuum in front of the gas bag and thereby reduce the resistance to the

movement of the latter and thus increase the velocity of the ship for a given expenditure of power, and further so that the propellers may rotate in a sufficiency of air space for elevating purposes without necessitating the suspension of the platform or frame of the car at any serious distance below the gas envelop.

In the preferred construction of semi-rigid air ship to which the invention is more particularly applicable, the car frame consists of two parallel girders extending from end to end of the gas envelop and supported by bands or ropes therefrom, the upper members of the frame being laced or otherwise secured close under the gas envelop.

In order to guard against disturbing the equipoise of the air ship by reason of unequal consumption of fuel by the engines (in the case in which the propellers are driven by liquid fuel internal combustion engines), both sets of engines are supplied with fuel from a common central fuel tank, or two or more central tanks which communicate with each other, such tank or tanks being preferably provided with baffles, so as to minimize washing of the liquid fuel.

For trimming purposes, the car is mounted upon the frame so as to be movable in a longitudinal direction, and this means of altering the center of mass of the air ship may also be used for the purpose of tilting the air ship so as to change its altitude.

The car frame is provided with wings or planes adapted to support the air ship, to maintain its longitudinal pose, and also to be used for the purpose of changing its altitude, for which purpose two pairs of such wings or planes are provided, one pair in front of and the other pair in rear of the center of mass of the air ship, these wings being hinged to the frame and being provided with means for raising and depressing them, either independently or simultaneously.

The invention is illustrated in the accompanying drawings in which—Figures 1 and 2 are respectively a side elevation and a plan view showing one way of mounting the engines and propellers; Figs. 3 and 4 are re-

95

100

spectively a part elevation of an air ship showing an alternative method of mounting and driving the propellers, and a plan view of the same, but with the gas envelop removed; Figs. 5 and 6 are respectively a side and a front elevation of the preferred construction of semi-rigid balloon to which type of air ship the present invention is more particularly designed to be applied, although it may also be applied to air ships of the rigid type. Figs. 7 and 8 are respectively a transverse section and a plan view of the car showing means for moving it translationally along the frame.

In the arrangement of Figs. 1 and 2 the engine *a*, shaft *b* and propeller *c* are mounted on trunnions *d* on a platform *e* which is rotatable on the track *f* by means of a circular rack *g* and pinion *g'*, the latter operated by a hand wheel *g''*. The platform *e* is confined by a flange or guide *f'* which, as shown may be integral with the track *f* and which engages over the upper side of the edge of the platform *e*. The movement of the propeller *c* in a vertical plane is effected by means of a rack *h* secured to the engine frame and pinion *h'*, the latter being operated by a handwheel *h''*. It will be seen that with this construction not only are the engine and propeller orientated simultaneously, but they are also tilted simultaneously and that there is a direct drive between the engine and the propeller.

In the construction shown in Figs. 3 and 4 the propeller shaft *b'* is driven from the engine through suitable gear such as chain *b''* and there is interposed between the chain drive and the propeller a universal joint *b'''* which enables the propeller to be tilted in a vertical plane with respect to the driving mechanism. While therefore, as in the arrangement of Figs. 1 and 2, the propeller and engine are orientated simultaneously so as not to disturb the balance of the airship, the propeller is tilted in a vertical plane without any corresponding movement of the engine. The elevating gear is represented by screwed shaft *i*, handwheel *i'* and slide *i''*, but obviously any other suitable mechanism may be used for this purpose.

Provision is made for freeing the platform *e* from the gear by which it is turned so that, for example, if one or both propellers have been turned in azimuth so as to change the course of the air ship, the propeller or propellers and the air ship may be allowed, by release of the setting gear, to swing into alignment with each other on the new course. For example, in the construction of Figs. 3 and 4 the pinion *g'* gearing with the circular rack *g* may be mounted on its shaft so that it can be shifted out of gear as by means of the pedal lever *g'''*.

The frame on which the engines are

mounted consists of two girder structures *j*, *k* suitably braced and stayed which extend from end to end of the gas bag and which are supported therefrom by bands or ropes *l* attached to the envelop, such supporting members being spaced at sufficiently frequent intervals and being of such comparatively short length that the whole structure is a semi-rigid one, that is to say that there is no sensible independent movement of the gas envelop and the frame supported by it. 75

Hinged to the frame on each side thereof are wings *m* these being arranged in oppositely disposed pairs of which one or more pairs are in front of the center of mass of the air ship and the other pair or pairs in rear thereof. These wings are provided with means (not shown in the drawing) for turning them about a longitudinal axis so that they can be made vertical or as nearly vertical as possible, or their inclination otherwise varied.

In the modified construction of semi-rigid balloons shown in Figs. 5 and 6, the upper members of the girder frame are laced directly to the gas envelop along the central part in the known manner and upon the ends of the main frame in the spaces between the top of the frame and the under-surface of the gas envelop are fixed auxiliary frames or stagings *n* upon which the ends of the envelop rest and to which they are laced. Covering one or both ends of the gas envelop is a shoe or cap *o* such as has already been proposed to provide support for girder frames and consisting preferably of aluminium plate, or other suitable light but rigid material, which shoe is rigidly secured to the auxiliary staging *n* and also to the gas envelop. As in this construction the central parts of the gas envelop rest directly upon the car frame, the elevating or supporting wings or planes, instead of being hinged to the upper members of the frame, would be hinged to brackets extending upwardly from the frame around the lower surface of the gas envelop to a sufficient height to allow the wings to be raised more or less into vertical planes. 110

The car *p* is preferably mounted so that it can be shifted longitudinally along the frame *j*, *k* through a sufficient distance as to enable the ship to be kept on an even keel, or to be tilted longitudinally in one direction or the other to an appreciable extent. With this object the car is provided with wheels *q* running upon longitudinal tracks *r* carried by the main frame on which also is supported a longitudinal rack *s*. The car is fitted with a pinion *t* which co-operates with the rack *s* and which by means of bevel gear *u* and handwheel *u'* can be rotated so as to traverse the car longitudinally in either direction. 125

Instead of single propellers at each end, each engine may be arranged to drive a pair of two-bladed propellers which may be of smaller diameter. The shafts of these 5 propellers are preferably set at a distance apart just somewhat greater than the length of a propeller blade, and in order that the propellers may rotate without interference, they are displaced 90° in phase and rotated 10 in opposite directions the blades of the propellers being appropriately set.

Having thus particularly described the nature of my said invention and the best means of carrying the same into practical 15 effect I claim:—

1. In an air-ship, the combination with a gas envelop of means for maneuvering the ship consisting of sets of associated engines and propellers mounted at the fore and aft 20 ends of the ship, every set being independent of the others, and devices whereby any one of the engines and the propeller associated with it may be vertically tilted simultaneously as well as orientated simultaneously 25 without altering the alinement of their shafts.

2. In an air-ship, the combination with a gas envelop of means for maneuvering the ship consisting of sets of associated engines 30 and propellers mounted at the fore and aft ends of the ship, every set being independent of the others, and devices whereby any one of the engines and the propellers associated with it may be vertically tilted simultaneously 35 as well as orientated simultaneously without altering the alinement of their shafts.

3. In an air-ship, the combination with a gas envelop of means for maneuvering the ship consisting of sets of associated engines 40 and propellers mounted at the fore and aft ends of the ship, every set being independent of the others, and devices whereby any one of the engines and the propeller associated with it may be vertically tilted simultaneously 45 as well as orientated simultaneously without altering the alinement of their shafts, each of said devices comprising a rotatable platform, bearings carried by the platform and adapted to pivotally support 50 an engine and its associated propeller, operable means for rotating the platform and swinging the engine and propeller in the bearings, and means for releasing the platform from the operable means so as to allow 55 the propeller and air ship to swing into alinement with each other.

4. In an air-ship, the combination with a gas envelop of means for maneuvering the ship consisting of sets of associated engines 60 and propellers mounted at the fore and aft ends of the ship, every set being independent of the others, and devices whereby any one of the engines and the propellers associated with it may be vertically tilted simultaneously

ously as well as orientated simultaneously 65 without altering the alinement of their shafts, each of said devices comprising a rotatable platform, bearings carried by the platform and adapted to pivotally support 70 an engine and its associated propeller, and operable means for rotating the platform and swinging the engine and propeller in the bearings.

5. In an air-ship, the combination with a gas envelop of means for maneuvering the ship consisting of sets of associated engines 75 and propellers mounted at the fore and aft ends of the ship, every set being independent of the others, and devices whereby any one of the engines and the propellers 80 associated with it may be vertically tilted simultaneously as well as orientated simultaneously without altering the alinement of their shafts, each of said devices comprising a rotatable platform, bearings carried by 85 the platform and adapted to pivotally support an engine and its associated propellers, operable means for rotating the platform and swinging the engine and propellers in the bearings, and means for releasing the 90 platform from the operable means so as to allow the propellers and air ship to swing into alinement with each other.

6. In an air-ship, the combination with a gas envelop of means for maneuvering the ship consisting of sets of liquid fuel internal combustion engines and propellers associated therewith, said sets of engines and propellers being mounted at the fore and aft ends of the ship and independent of one 95 another, a liquid fuel tank common to all the engines and in controlled communication therewith, and devices whereby any one of the engines and the propeller associated with it may be vertically tilted simultaneously 100 as well as orientated simultaneously without altering the alinement of their shafts.

7. In an air-ship, the combination with a gas envelop of means for maneuvering the ship consisting of sets of liquid fuel internal combustion engines and propellers associated therewith, said sets of engines and propellers being mounted at the fore and aft ends of the ship and independent of one 110 another, a plurality of liquid fuel tanks communicating with each other and with all the engines, and devices whereby any one of the engines and the propeller associated with it may be vertically tilted simultaneously 115 as well as orientated simultaneously without altering the alinement of their shafts.

8. In an air-ship, the combination with a gas envelop of means for maneuvering the ship consisting of a frame supported from the envelop, a car mounted on said frame so 120 as to be movable fore and aft to tilt the air ship to change its altitude, sets of associated engines and propellers mounted at each end 125

of the frame, every set being independent of the others and devices whereby any one of the engines and the propeller associated with it may be vertically tilted simultaneously as well as orientated simultaneously without altering the alignment of their shafts.

In testimony whereof I have signed my

name to this specification in the presence of two subscribing witnesses.
